539,650 A	5/1895	Searle
558,814 A	4/1896	Hunt

FIG. 1 is a front perspective view of a lock showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines illustrate the unclaimed portions and form no part of the claimed design.
